(57) **CLAIM**

The ornamental design for a taillight for a vehicle as shown and described.

DESCRIPTION

FIG. 1 is a front view of a taillight for a vehicle according to the design;

FIG. 2 is a left, bottom perspective view thereof;

FIG. 3 is a right, front perspective view thereof;

FIG. 4 is a left side view thereof;

FIG. 5 is a right side view thereof;

FIG. 6 is a top view thereof;

FIG. 7 is a bottom view thereof; and,

FIG. 8 is a rear view thereof.

The broken lines in the drawings indicate a boundary between claimed and unclaimed portions and form no part of the claim. The deemphasized, grayscale portions shown inside the broken line boundaries form no part of the claimed design.

1 Claim, 8 Drawing Sheets
